(57) **CLAIM**

The ornamental design for a keycap as shown and described.

DESCRIPTION

FIG. 1 is a perspective view of a keycap showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a cross-sectional view taken in the direction of line 8-8 in FIG. 7;

FIG. 9 is an enlarged view of the portion, labeled '9' of FIG. 8; and,

FIG. 10 is a perspective view showing the keycap in the state of use.

The evenly-dashed broken lines illustrate portions of the keycap that form no part of the claimed design. The oblique line shading used in the drawings indicates that the surface is transparent. The dot-dash broken lines in FIG. 7 illustrating the cross-section line form no part of the claimed design. The dot-dot-dash broken lines in FIGS. 8, 9 and 10 illustrate the boundaries of the enlarged portions and form no part of the claimed design. The evenly-dashed broken lines in FIG. 10 are for the purpose of depicting environment and form no part of the claimed design.
